Primary Examiner—Louis S. Zarfas

Assistant Examiner—Daniel Yu

(74) **Attorney, Agent, or Firm**—Nelson Mullins Riley & Scarborough, LLP

(57) **CLAIM**

The ornamental design for a dispensing container, substantially as shown and described.

DESCRIPTION

FIG. 1 illustrates a perspective view of an embodiment of the present dispensing container;

FIG. 2 shows a side view of the dispensing container illustrated in FIG. 1;

FIG. 3 shows the front view of the dispensing container;

FIG. 4 shows the rear view of the dispensing container;

FIG. 5 shows the top view of the dispensing container;

FIG. 6 shows the bottom view of the dispensing container; and,

FIG. 7 is a perspective view of the dispensing container illustrating the container after breakage of the breakable seal and removal of the tab to expose the outlet.
